C. M. French.

Plow.

No 78869

Patented Jun. 16, 1868.

UNITED STATES PATENT OFFICE.

C. M. FRENCH, OF ROCHESTER, PENNSYLVANIA.

IMPROVEMENT IN PLOWS.

Specification forming part of Letters Patent No. 78,869, dated June 16, 1868.

To all whom it may concern:

Be it known that I, CHARLES M. FRENCH, of Rochester, in the county of Beaver and State of Pennsylvania, have invented a new and useful Improvement in Plows; and I do hereby declare that the following is a full and exact description thereof, reference being had to the accompanying drawings, and to the letters of reference marked thereon.

The nature of my invention, consists in so constructing a plow that the joint between the share and mold-board shall be straight and on a line at right angle to the longitudinal plane of the share-bar, said joint, share, and mold-board being so arranged with relation to each other as to give strength and depth to the share-bar at the point where the line of the joint between the share and mold-board crosses the longitudinal plane of the share-bar, the whole being constructed, arranged, and operating in the manner hereinafter described.

To enable others skilled in the art to make and use my invention, I will proceed to describe its construction and operation.

In the accompanying drawings, which form part of my specification, Figure 1 is a perspective view of my improvement in plows. Fig. 2 is a section of the plow, and represents a side or face view of the share-bar and landside.

In the drawings, *g* represents the mold-board; *C*, the share; *X*, the standard; *h*, the cutter; *f*, the share-bar; *D*, the landside; *1, 2, 3, 4, 5, 6*, and *7*, the bolts for securing the several parts together.

The mold-board, share, share-bar, landside, and cutter are made of cast-steel. The standard *X* is made of cast-iron, and made in any of the forms used for the construction of steel plows; but in every case the contour of the lower part of the standard *X* must correspond to the form of the parts which are to be attached to it. The beam and handles of the plow are constructed of wood and made in any of the known forms, and are secured to the standard *X*, mold-board *g*, landside *D*, and share-bar *f* by means of the bolts marked *2, 3, and 7*. The plowshare *C* and share-bar *f* are usually made in one part by being welded together at the point indicated by the curved and dotted line *o* shown in Fig. 2. The landside *D* is formed from flat bars of cast-steel, which are cut to the form and size of the pattern for the desired landside. The mold-board is made from sheets of cast-steel, which are

cut to the form and size of the pattern desired for the mold-board, and by the use of a metal former is bent to the desired curvature.

The share *C* and its bar *f* are secured to the standard *X* by means of the bolt *5*, and the mold-board *g* is secured in its position on the standard *X* by means of the bolts marked *1*. The landside is secured to the standard *X* by means of the bolts *4*. The lower end of the cutter is fitted in a cavity made in the share, as shown at the point marked *n*, and the upper end is secured to the standard *X* by means of the bolts *6*.

By making the joint *A* between the share *C* and mold-board *g* straight and on a line at right angle to the longitudinal plane of the landside depth and strength will be given to the share bar *f* at the point *B*, and the shoulder *e* will be formed for the point of the landside *D* to rest against, and the sharp point (indicated by the dotted lines around letter *B* in Fig. 2) will be avoided. This sharp point, when made part of the landside, is very liable to become bent and catch the fine roots or other fiber in the ground.

By making the joint *A* in the manner described the joint can be planed in a planing-machine and fitted perfectly true, and by the general construction of the plow the several parts can be easily and with great facility duplicated when desired.

I wish it clearly understood that I do not claim broadly a straight joint between the plowshare and mold-board; but,

Having thus described the nature and construction of my improvement, what I claim as of my invention is—

So constructing a plow as that the joint between the share and mold-board shall be about on a line at right angle to the plane of the share bar or landside of the plow, said joint being so arranged with relation to the share and mold-board as to give depth and strength to the forward part of the share-bar, and also so that the several parts may be duplicated, the whole being constructed, arranged, and operating substantially as herein described, and for the purpose set forth.

C. M. FRENCH.
